[57] CLAIM

The ornamental design for a tool handle, as shown and described.

DESCRIPTION

FIG. 1 is a perspective view of a tool handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof, the broken line portion being for illustrative purposes only and forming no part of the claimed design; and

FIG. 9 is another front elevational view thereof, the broken line portion being for illustrative purposes only and forming no part of the claimed design.

The broken lines showing the hammer head in FIG. 8 and the axe head in FIG. 9 are for illustrative purposes only and form no part of the claimed design.

FIG. 1

FIG. 2

FIG. 3
